(57) **CLAIM**

The ornamental design for a pillow covering, as shown and described.

DESCRIPTION

FIG. 1 is a top view of a pillow covering as it would appear upon a square shaped pillow.

FIG. 2 is a bottom view of the pillow covering as it would appear on a square shaped pillow.

FIG. 3 is a front view of the pillow covering as it would appear on a square shaped pillow.

FIG. 4 is a rear view of the pillow covering as it would appear on a square shaped pillow.

FIG. 5 is a right side view of the pillow covering as it would appear on a square shaped pillow; and,

FIG. 6 is a left side view of the pillow covering as it would appear on a square shaped pillow.

The broken lines in the above figures depict stitching.
